(Continued)

Primary Examiner — Ralf Seifert(74) *Attorney, Agent, or Firm* — Reinhart Boerner Van Deuren P.C.(57) **CLAIM**

I claim the ornamental design for a compressor, as shown and described.

DESCRIPTION

The design application contains at least one drawing executed in color. Copies of this design application publication with color drawings will be provided by the Office upon request and payment of the necessary fee.

FIG. 1 is a perspective view from the front and left hand side of a compressor of a first embodiment;

FIG. 2 is a front view thereof;

FIG. 3 is a left side view thereof;

FIG. 4 is a right view thereof;

FIG. 5 is a rear view thereof;

FIG. 6 is a top view thereof;

FIG. 7 is a bottom view thereof.

FIG. 8 is a perspective view from the front and left hand side of a compressor employing green color according to a second embodiment:

FIG. 9 is a front view thereof;

FIG. 10 is a left side view thereof;

FIG. 11 is a right view thereof;

FIG. 12 is a rear view thereof;

FIG. 13 is a top view thereof; and,

FIG. 14 is a bottom view thereof.

1 Claim, 14 Drawing Sheets
(7 of 14 Drawing Sheet(s) Filed in Color)
